UNITED STATES PATENT OFFICE.

JAMES H. RAND, JR., OF TONAWANDA, NEW YORK, ASSIGNOR, BY MESNE ASSIGNMENTS, TO REMINGTON RAND, INC., OF NEW YORK, N. Y., A CORPORATION OF DELAWARE.

INDEX DEVICE.

Application filed July 31, 1924. Serial No. 729,276.

This invention relates to card index or record devices.

Heretofore card index or record devices have been provided comprising generally a series of hinged record or index displaying members arranged substantially flatwise on a tray or support and having means for holding the cards or displaying members in overlapping arrangement with the edges of the cards projecting one beyond another, whereby the index or record matter adjacent the edges of the cards may be readily viewed. Heretofore, this overlapping arrangement or spacing of the cards or record displaying members has been attained, for example by parts on such members which are secured to and adapted to extend angularly away from said members to permit said members to nest by inserting the edge of one member between another member and its secured part.

Another form of member is provided with a part against which another member and its part is adapted to abut to effect the desired spacing. Such cards or record displaying

members have usually been provided with parts engaging portions at the sides of the tray or supports, whereby the cards or members are held in the tray in either the nested or abutting and overlapping arrangement.

Certain disadvantages have attended the use of structures such as described in that, in use, the securing portions of the record displaying members which cooperate with the side portions of the tray or support become bent, resulting in portions of the record displaying member being raised or displaced from the normal level of the cards, centrally of the tray or support. Thus, by misalignment of portions of the record displaying member, as the record displaying members are individually slid or moved on the tray, the members do not contact or nest properly with one another, and the desired overlapping relationship is not consistently maintained.

The objects of the present invention are to provide a card index in which the hinged cards or record displaying members are positively guided to the desired nesting or interengaging positions; also to provide a card index in which the portions of the hinged cards or card displaying members engaging the supporting parts on the tray or supports, are prevented from becoming distort-

ed and in which the interengaging parts of the several cards or card displaying members are always in proper alignment; also to provide a card index or record device in which cards or record displaying members of greater than usual width may be used and the cards or record displaying members still be maintained in proper overlapping spaced relation; and also to provide improvements in card and record devices in the other respects hereinafter set forth and claimed.

In the drawings:

Fig. 1 is a plan view of a portion of an index device embodying the present invention.

Fig. 2 is a transverse section thereof on an enlarged scale, showing one edge of one of the cards partially removed from the tray or support.

Fig. 3 is a fragmentary, transverse sectional elevation illustrating one of the steps in the method of attaching the cards or card holders to the tray or support.

Fig. 4 is a plan view of another form of a record device having means according to the present invention for attaching the cards to a tray or support.

Fig. 5 is a longitudinal section on line 5—5, Fig. 1, of the record device.

Fig. 6 is a similar section on line 6—6, Fig. 4.

Fig. 7 is a rear elevation of a portion of a holder of slightly different form to that shown in Figs. 2, 3, 5 and 6.

Fig. 8 is a rear elevation of another slightly modified form of holder.

Fig. 9 is a section through an index device including the form shown in Fig. 8.

In this description, the term "record displaying member" is used to designate a card on which record or index matter may be inscribed or displayed, or a separate holder adapted to be secured in the tray or support, and on which separate record or index cards bearing the record or index material may be placed or displayed.

In Fig. 1 of the drawings, 10 designates a plurality of record displaying members arranged in a tray or slide 11 in overlapping relation so that an edge of each record displaying member projects beyond the edge of the record displaying members next above. In the particular embodiment

shown, the record displaying members consist of body portions 12 which are hinged to lugs 13 by means of weakened or perforated hinge lines 13^b so that the record displaying members are connected to the slide or support. The slide or support is preferably formed with side flanges 14 beneath which the outer ends 15 of the lugs 13 engage. In the particular form of record device illustrated in Fig. 5, the lug of each record displaying member is adapted to nest between the lug and the body portion of the next record displaying member, whereby those members are held in the proper overlapping relation. As illustrated in Fig. 2, the record displaying members may be removed from or inserted in the tray by flexing or bending the lugs so that the outer ends or tongues 15 of the lugs are permitted to escape from or are inserted under the side flanges 14 of the tray or supports.

In order to secure positive guidance for the record displaying members and their lugs or attaching means as they are moved in the tray, so that proper nesting or interengagement of the parts will be effected to secure the desired overlapping relation, means are provided, preferably between the side edges of the record displaying members for preventing buckling or distortion of the record displaying members or their lugs, and preferably for causing these members to travel in a common plane in their sliding movements in the slide or support 11. In the embodiment shown for this purpose, there are provided intermediate opposing lug tongues, or members such for example as indicated at 16, which engage suitable and preferably fixed parts on the slide or support. In the embodiment shown, the oppositely directed flanges 17 of the rail 18 constitute these fixed parts, these rails being suitably secured, in the particular embodiment illustrated, to the bottom 19 of the tray. The intermediate lugs cooperate with the side or outer lugs or tongues 15 and insure movement of the record displaying members constituting the series in the tray in the same plane, thereby preventing buckling or distortion of the record displaying members or their attaching lugs and providing positive guides to insure proper interengagement of the parts so as to secure the desired overlapping arrangement.

Fig. 3 illustrates the method of engaging the intermediate lugs 16 with the flanges 17 on the tray or slide. To effect such engagement, the record displaying member 10 may be flexed as shown in Fig. 3 and then the ends released so that the intermediate lugs will take a position underneath the flanges 17, as shown in Fig. 2. As illustrated at the right hand side of Fig. 2, the end or side edge lugs are then inserted under the side rails or flanges 14 of the tray by flexing

the portions of the lugs or of the record displaying member between the intermediate lugs and the side edges, and when that portion is released, the outer or side edge lugs will rest beneath the side flanges or rails, as shown at the left hand side of Fig. 2.

In the modified form shown in Figs. 4 and 6, the body portion 12 of the record displaying members are hinged to spacing lugs of somewhat different structure from those shown in the other figures, these lugs 13^a constituting relatively thick bodies of material and being adapted to rest in a plane parallel with the tray bottom with their edges in contact as shown in Fig. 6, and in substantially horizontal alinement. In this form the intermediate flanges or rails 17^a may, as illustrated, be fixed to the bottom 19 of the tray, to engage intermediate tongues 16^a of the attaching lugs and function in the manner as described for the other figures of drawing.

As illustrated in Figs. 2 and 9, the side flanges 14 of the tray preferably extend inwardly of the body of the tray and are set down a distance below the upper edges of the tray sides. This permits of the provision on the record displaying member of means for overlapping the inner edge portions 20 of the set down flanges whereby the record displaying members are held more firmly in desired alinement. For this purpose, referring to Figs. 8 and 9, the outer edge portion of the record displaying member may be provided with upper and lower tongues or cooperating portions 21 and 22. These tongues overlap the side rails or flanges of the tray or slide, and in combination with the intermediate tongues, ensure that the record displaying members will be moved in a definite plane when shifted or slid on the support and will always nest or engage properly to maintain the desired spaced relation. At the same time the record displaying members are so firmly secured to the support or slide that the slide or support may be lifted or moved from place to place by utilizing one or more of the record displaying members as a handle, the connections between the record displaying members and the tray or slide permitting this to be done without disengaging the record displaying members from the tray or slide.

The form shown in Fig. 7 displays a modification in the form of the inner tongue portions over the form shown in Figs. 1, 2, 3, 8 and 9. In this form, the lug member 13^b is not severed intermediately of its ends but is continuous and is provided with a recessed portion providing the intermediate tongues 16^b.

As shown in Figs. 5, 7 and 8, the lug of the record displaying member is provided with beveled or angular edges 24. These

angular edges make the lugs more nearly rigid and prevent buckling or unintentional flexing thereof out of a straight line. This is also for the further purpose of facilitating nesting and proper inter-engagement of the record displaying members to effect the proper spaced arrangement of the members. It further strengthens the intermediate and outer tongues of the lugs and provides a more firm connection of the tongue to the tray or support.

I claim as my invention:—

- 5 1. A record-displaying member having a plurality of coplanar retaining tongues adjacent one edge thereof, one of said tongues being positioned adjacent one side edge of said displaying member, and another of said tongues being positioned adjacent the opposite side edge of said displaying member, a pair of said tongues being oppositely directed and positioned intermediately of said side edges, and a support having parts for engaging said tongues to maintain said displaying member on said support.
- 10 2. In a record device, a card having parts for displaying record or index matter, a pair of lugs hinged to said card for securing said card on a support, said lugs extending transversely of said card adjacent one end thereof, a support for said card having side parts adapted to engage the outer ends of said lugs to maintain said card on said support, the inner adjacent ends of said lugs being spaced apart and oppositely directed and adapted to engage a holding part on said support between said side parts.
- 15 3. In a record device, a leaf for supporting a plurality of cards or the like in desired arrangement, opposite side members on said leaf for engaging portions of said cards to maintain said cards connected to said leaf and intermediate members on said leaf between the sides, a plurality of cards, each of said cards having a pair of relatively heavy attaching lugs extending transversely of said leaf, the lugs of each card having parts for engaging the opposite side members of said leaf and intermediate parts having oppositely directed ends for engaging the intermediate members of said leaf, and card bodies flexibly secured to said lugs.
- 20 4. In a record device, a leaf having a bottom, card-engaging side rails having portions spaced from the bottom of said leaf, a pair of intermediate card-engaging rails between the sides of said leaf, a card having a record-displaying portion and a pair of attaching lugs, said lugs having outer end portions engaging the undersides of said side rails and inner end portions engaging the undersides of said intermediate rails for releasably maintaining said card connected to said tray and preventing unintentional flexure of said lug or said card.
- 25 5. In a card index device, a tray, a plurality of cards disposed substantially flatwise in overlapping arrangement in said tray, flat attaching lugs on said cards, said lugs having support-engaging parts at their ends at opposite side edges of said cards, and having intermediate oppositely directed support-engaging parts between the side edges of said cards, and parts on said tray adapted to engage said end and said intermediate support engaging parts for releasably maintaining said cards connected to said tray and said lugs against unintentional movement or flexure from their flat form.
- 30 6. In a record device, a card having a plurality of retaining tongues, one of said tongues being positioned adjacent one side edge of said displaying member, another of said tongues being positioned adjacent the opposite side edge of said displaying member, and a pair of said tongues being oppositely directed and positioned intermediately of said side edges.
- 35 7. In a record device, a card having retaining tongues adjacent opposite ends on one marginal portion extending in opposite directions, and other retaining tongues on said marginal portion intermediate said first-mentioned tongues extending in opposed relation, all said tongues being adapted for interlocking cooperation with a support.
- 40 8. In a record device, a card having a pair of retaining tongues at opposite ends of one marginal portion, and another pair of retaining tongues intermediate said first-mentioned tongues, all of said tongues being formed for interlocking cooperation with a suitable support.
